TOILET ARTICLE CONSTRUCTION

Royce H. Potts, Brooklyn, N. Y., assignor to Ramel Manufacturing Co., Inc., New York, N. Y., a corporation of New York

Application February 15, 1937, Serial No. 125,685

2 Claims. (Cl. 88—102)

This invention relates to a construction for toilet articles, more particularly such toilet articles, as mirrors, brushes and the like.

In constructing toilet articles such as hand mirrors, hand brushes or the like, a mirror or brush back is maintained within a frame terminating into a handle portion. Such construction usually employs a thin metal frame of general V-shaped or U-shaped construction, split at one portion of the perimeter or periphery, and with the split portions tensioned against an enveloping handle for the split portions. Such frames have been made from thin metal stock and can withstand the tensioning forces incident to attachment of the handle. Such construction is generally shown in the patent to Bomeisler 820,621, May 15, 1906.

A construction of the character referred to in the Bomeisler patent has, for a great many years, formed the foundation for such toilet articles as hereinabove referred to, in the form of hand mirrors, brushes or the like. There are limitations, however, in such articles in that the employment of a thin metal frame in which the terminal edges thereof are tensioned against the handle, requires the employment of rather simple frame outlines, while incorporating a material which is to form the frame capable of withstanding the stresses incident to an attachment of the handle portion, as requisite rigidity necessitates that the portion of the frame which is coupled to the handle withstand such tensioning stresses. This has resulted in limitations in ornamental configurations which may be given to the toilet articles of the character referred to, as well as a limitation in the materials from which the toilet article parts may be formed.

With the advent of methods for forming articles by die casting, stamping, extrusion or injection casting methods, employing metals or plastics, such raw materials are amenable to modification to configurations of intricate contour as well as providing the color characteristics of highly ornamental aspect.

The embodiment of such materials into toilet articles of the character herein referred to, has its limitations by reason of the fact that these materials lack the tensile strength characteristics of the metals employed in the framed articles of the Bomeisler patent.

Accordingly, it is an object of my invention to provide a toilet article construction particularly in the form of hand mirrors, brushes or the like, which permits the employment of the castable metals or plastics and the incorporation

thereof into such toilet articles, of inexpensive yet rigid and durable construction.

It is further contemplated by my invention to provide a toilet article construction, such as holders for mirrors, brushes and the like, in which the mirror or brush frame may be formed from metals by a die casting or ordinary metal casting method, or by a stamping method or by the so-called injection casting method, whereby intricate forms, as well as the ornamental characteristics of these materials may be embodied into highly ornamental and pleasing contours, thereby eliminating very expensive finishing operations, yet permitting color schemes of highly aesthetic character.

A further object of my invention resides in the provision of a toilet article construction, such as holders for mirrors, brushes and the like, in which the holder for the mirror, brush or the like, in the form of a frame, and the handle for the same, are of moldable elements, as distinguished from an integral construction of the brush or mirror back and handle, which provides a rigid and durable construction yet permitting the employment of metal castings or thin walled stampings or, more particularly, thermoplastic materials such as the phenol formaldehyde resins, such as cellulose acetate, urea resins, and which may be formed by a die casting, stamping or injection casting method, or ordinary casting.

To attain these objects and such further objects as may appear herein or be hereinafter pointed out, I make reference to the accompanying drawing, forming a part hereof, in which—

Figure 1 is a plan view showing one embodiment of my invention;

Figure 2 is a section taken on the line 2—2 of Figure 1;

Figure 3 is a section taken on the line 3—3 of Figure 1;

Figure 4 is a fragmentary perspective view of the top of the frame;

Figure 5 is a fragmentary perspective view of the lower portion of the frame;

Figures 6 and 7, respectively, are fragmentary perspective views of two embodiments of frame constructions, adjacent the crown portion;

Figure 8 is a sectional view corresponding to Figure 3, of another embodiment of frame construction;

Figure 9 is a sectional view of a mirror frame corresponding to Figure 3, with a still further embodiment of frame construction;

Figure 10 is a perspective view of a one-piece

frame construction forming still another embodiment of my invention.

Making reference to the drawing, the invention is illustrated in connection with a toilet article in the form of a hand mirror 10, it being understood that while I have so illustrated my invention, the novel phases of my invention have equal applicability to a hand hair brush or similar toilet article.

10 In the views, in the embodiment illustrated in Figures 1 to 5, I provide a frame 11, made of a pair of sections 12 and 13 of symmetrical contour, channelled interiorly at 14 to provide a U-shaped or V-shaped channel, and exteriorly 15 at 15, in any desired configuration.

The sections 12 and 13 terminate at their upper portion in lugs 16 and 17, at one end thereof, and into downwardly depending tangs 18 and 19 at the opposite end, the tangs 18 and 19 being 20 channelled to provide an orifice 20, for purposes which will appear more clearly as this description proceeds.

A novel phase of my invention is to provide a frame 11 from the sections 12 and 13, as described, from castable material, particularly that which is amenable to die casting or ordinary casting or injection molding. Preferably the materials constituting the frame sections 12 and 13 are made from synthetic plastics, such as the 30 phenol formaldehyde molding powders, though synthetic plastics which are amenable to casting by the injection casting process may be employed, and I have particular reference to synthetic plastics, such as cellulose acetate, which may be employed to cast the frame sections 12 and 13 by the so-called injection casting process.

While it is preferred to make the frame of castable materials by any one of the processes described, to a certain extent thin metal stampings may be employed. These materials have not found utility in the art to which this invention relates, so far as known to me, in that they are not susceptible of resisting the tensile stresses in making a two part mirror or brush back and 45 handle therefor.

The restriction to so-called drawn or rolled metal, limited the peripheral configuration of the toilet articles, as contemplated by me, as well as limiting the article to so-called metal 50 finishes.

As my invention contemplates the incorporation in two part articles, i. e. a body and a handle, of castable materials, particularly the metals susceptible of die casting or ordinary casting or the plastics susceptible of molding, casting or injection casting, I will now refer to a construction or assembly constituting my invention wherein such castable materials may be employed, thereby to enable me to obtain a wide range of ornamental contours as well as the ornamental characteristics incident to the employment of 55 such castable materials.

Accordingly, having determined the frame contour and having cast the sections 12 and 13 with the external contour and the internal channel, as previously described, I provide a facing member in the form of a mirror 21, corresponding to the contour of the frame and capable of being received within the channel portion 14 thereof. It will be understood, however, that this facing member 21 may be the back or pad of a brush where the toilet article is to be such form of article.

Additionally, I provide a plate 22, dished outwardly as more clearly apparent in Figure 2.

also corresponding in contour to the frame and of a dimension to be received within the channel portion 14 thereof. This plate is of rather stiff metal and forms an essential feature of my invention in conjunction with a frame contemplated by my invention, and as this plate more or less forms the foundation for the frame when received within the channel 14 of said frame, this will hereinafter be referred to as a frame plate.

10 A rod 23 is provided, including a flattened upper end 24, which is affixed to the plate 22 by rivets 25. It will be understood, however, that such connection between the portion 24 and the frame plate 22 may be accomplished by spot welding, brazing or otherwise.

Additionally, also, an ornamental back plate 26 may be provided, pressed, molded or otherwise, to lie flat against the frame plate 22 and this may be made from celluloid or laminations of 20 paper and celluloid or a molded or cast blank, to carry forward some ornamental motif on the exterior surface of the back 26.

With the mirror 21, frame plate 22 and back plate 26 thus provided, these may be stacked in 25 the order shown, including between the frame plate and mirror 21, filler pieces 27 and 28. This assembly is then inserted within the frame 11, to have the peripheral edges lie within the channel 14, and with the handle rod 23 extending 30 between the tangs 18 and 19, through the boring 20 provided therebetween.

In this assembled relationship, with the parts so held by some holder, the lugs 16 and 17 are connected to each other by a transverse screw 35 or pin 29. Thereupon a ferrule 30 is sleeved over the tangs 18 and 19 and the handle rod disposed therebetween. The ferrule has a boring 31, corresponding to the external dimensions of the tangs 18 and 19 to snugly draw the tangs 18 40 and 19 towards each other. Extensions 32 and 33 overlie the front and rear faces of the frame adjacent the tangs 18 and 19, in a manner which will be readily understood.

The ferrule 30 is preferably formed with an 45 externally stepped shoulder 34, adapted to receive the upper end of the hollow handle 35, when this is sleeved over the handle rod 23.

The handle 35 is terminated short of the end 36 of the handle rod 23, which end is screw-threaded and arranged to be received by the keying nut 37, having a flange 38 and extension 39, directed interiorly of the sleeved handle 35.

The construction described will be readily understood to provide a rigidly integrated assembly 55 in that the frame plate serves as the skeleton or foundation for the frame, permitting the tensioning of the frame against the frame plate through the tension exerted against the handle rod in operating the nut 37 against the handle 35 and the ferrule 30, binding the tangs 18 and 19 into this portion of the ferrule.

Thus, by providing the frame plate and handle rod in the manner as described, in the nature of a skeleton for the frame 11, the frame is not utilized for resisting tensile stresses and permits the employment of the castable materials, thereby to permit any desired configuration or contour to be given to the frame, in addition to employing the castable materials aforementioned.

70 In the assembly shown, additional ornamental contour may be given to the toilet article by overlapping the lugs 16 and 17 with the crown portion held in position by a suitable cement 75

which may be soft solder, pitch or some thermoplastic material. Thus the lugs 16 and 17 may be enveloped by the crown portion 40, to impart desirable ornamental contours to the assembly of this portion.

In Figure 6 I have shown a fragmentary portion of a frame in which the lugs 16 and 17 are provided with keying slots 16a, so that when the crown portion 40 is enveloped over the lugs, cementing material 41, such as pitch, which is poured in the intervening space between the lugs and the crown portion 40, will flow into the keying portions 16a and rigidly connect the crown portion to the lugs.

In Figure 7 the sections of the frame 12 and 13 have the lugs 16 and 17 provided with cutouts 17a, forming an orifice. To connect the crown 40 to the lugs 16 and 17, in the embodiment shown in Figure 2, a transverse pin 41a may be directed through the crown portion to engage the orifice 17a.

In Figure 8 I have shown a fragmentary sectional view of a frame 12a, which where employing the castable material hereinbefore described, may be formed with a pair of spaced channels 14a and 14b, into which, respectively, may be disposed the mirror 21, the frame plate 22 and the back plate 26. The casting material thereby is amenable to a contour which eliminates the need for the filler plates 27 and 28, but otherwise providing the rigid construction having novelty already described.

In Figure 9 I have illustrated a still further embodiment of my invention wherein the frame sections may be split in a plane parallel to the plane of the mirror. Such construction permits of a one piece frame comprising a front frame section 11a and a rear section 11b, contacting at contiguous faces 12b, and connected by the pin 13b, and forming an internal channel 14c, into which may be disposed the peripheral edges of the mirror frame plate 22, back plate 26 and interposed filler pieces 27 and 28, in the manner readily understood.

In Figure 10 I have illustrated a still further embodiment of my invention in which a one piece frame 15b is provided and may be made of the castable material hereinbefore described. This frame is split adjacent the lower portion to provide tangs 18a and 19a. The frame is otherwise formed interiorly thereof, adjacent the periphery, with a channel 14d, continuing thru the tangs 18a and 19a and thereby forming a boring 20a, through which the handle rod may be disposed when combined with the handle assembly of the character illustrated in Figures 1 and 2.

In the embodiment illustrated in Figure 9, where the material constituting the sections 11a and 11b is a solvent activatable material, such as cellulose acetate or activatable by a thermoplastic adhesive, the contiguous contacting faces of these sections may be cemented together, employing such an activating agent with heat and/or pressure to effect union between the sections 11a and 11b at the time of, or prior to assembly with the facing member, frame plate, back plate and filler members.

It will also be observed that though I have described the sections 12 and 13 as connectible by lugs 16 and 17, disposed as extensions outside of the frame contour, affixation may be effected by overlapping and the connecting portions directed to conform to the contour of the chan-

nelled section at this portion by an overlapping joint.

It will also be observed that while I have illustrated and specifically described the handle member 35 and the ferrule 30 as separable members, these may be integrally formed or connected together before connection with the frame assembly, without departing from the spirit of my invention.

It will thus be observed that there has been provided a rigid assembly for a toilet article, in which the frame and handle may be of a plural part construction and in which the frame is rigidly integrated while permitting the employment of low tensile strength materials which are amenable to shaping and forming operations, to impart desirable ornamental exterior contours to the frame.

In the claims, where I have referred to "low tensile strength" material, I mean to include thereby castable materials, such as the metals which are susceptible of die casting or ordinary metal casting operations, and thermoplastic materials, such as moldable synthetic resins, die castable thermoplastic synthetic resins and die castable or injection castable synthetic thermoplastics, of which the cellulose compounds, with or without the addition of plasticizers and resins, for example, cellulose acetate, plasticized nitro cellulose, Tenite (cellulose acetate), may be exemplified.

Having thus described my invention and illustrated its use, what I claim as new and desire to secure by Letters Patent, is—

1. A toilet article of the character described comprising, in combination, a channelled frame of die cast material amenable to shaping and forming operations to impart an ornamental exterior contour thereto, said frame being split substantially diametrically, one of said split portions rendering said frame distensible when the other is held together, extensions comprising tangs adjacent one of said split portions, extensions substantially diametrically opposite to said tangs, means for binding said last named extensions together including an enveloping crown housing, a facing member and a rigid frame plate having their peripheral portions seated in said channelled frame, a handle rod secured to said frame plate extending radially through said frame between said tangs, a ferrule sleeved over said tangs, a handle sleeved over said handle rod and engaging said ferrule, said handle rod extending through said handle and an anchoring member engaging the free end of said handle rod and positioned against said handle and the ferrule to hold said handle to and against said frame in a rigid assembly.

2. A toilet article of the character described comprising in combination, a channelled frame of low tensile strength material, amenable to shaping for forming operations to impart ornamental contour effects thereto but of itself insufficient to resist the stresses of use of said article, said frame being split permitting the insertion of plates therebetween to be seated in the channelled portion of said frame, the channel continuing through extensions adjacent said split portion comprising tangs angularly directed from said frame and providing lateral channel portions forming with each other a butt joint, a stiffening plate seated in said channel having a portion rigidly attached thereto and extending through the boring formed by said tangs and being formed with a fastening connection at its 75

end, a ferrule sleeved over said tangs and engaging the opposite faces of said frame on the exterior thereof and enveloping said tanks and having anchoring means engaging the fastening connection at one side to draw the plate against the interior section of the channel adjacent the split portion and at the other side to force

the ferrule against the exterior portion of the frame and to draw the lateral portions of said tangs in butt joint engagement whereby a handle secured to said ferrule will be held in rigid assembly with said frame. 5

ROYCE H. POTTS.
